UNITED STATES PATENT OFFICE.

JACOB ANDRESEN, OF MINNEAPOLIS, MINNESOTA.

ELECTRICALLY-ILLUMINATED FIREPROOF CHRISTMAS WREATH.

Application filed November 7, 1921. Serial No. 513,332.

To all whom it may concern:

Be it known that I, JACOB ANDRESEN, a citizen of the United States, residing at Minneapolis, in the county of Hennepin and 5 State of Minnesota, have invented certain new and useful Improvements in Electrically-Illuminated Fireproof Christmas Wreaths; and I do hereby declare the following to be a full, clear, and exact description of the invention, such as will enable others skilled in the art to which it appertains to make and use the same.

My invention has for its object to provide an electrically illuminated fire-proof Christmas wreath, and to this end, it consists of the 15 novel devices and combinations of devices hereinafter described and defined in the claims.

As is well known, it is a growing custom 20 to place candles in windows on Christmas eve, but owing to the danger of thus starting fires in the curtains, draperies and shades, the custom has been more or less discouraged by officials. By the use of my invention all such danger is eliminated.

In the accompanying drawings, which illustrate the invention, like characters indicate like parts throughout the several views.

Referring to the drawings:

30 Fig. 1 is a view in elevation of the invention with some parts broken away;

Fig. 2 is a view partly in elevation and partly in section taken on the line 2-2 in Fig. 1 on an enlarged scale;

35 Fig. 3 is a fragmentary detail view with some parts sectioned and illustrating one method of attaching the wreaths to the hoop; and

Fig. 4 shows a modified means for attaching the light fixture to the hoop.

Referring first to the invention as shown in Figs. 1 to 3 inclusive, the numeral 5 indicates a transversely divided hoop, which, as shown, is formed from a single piece of 45 relatively heavy wire, the ends of which are inserted into a socket-like coupling 6, at diametrically opposite points, and rigidly secured thereto by any suitable means.

A screw-threaded stem 7 extends radially 50 into the hoop 5 and has screw-threaded engagement with the coupling 6 for endwise adjustment, and a cap 8 has screw-threaded engagement with the inner end of the stem 7 for adjustment thereon. Supported on the 55 cap 8 and secured thereto by a screw 9, is a lamp socket 10 of porcelain or other insulat-

ing material, and a light bulb 11, designed to represent a candle flame, is mounted in said lamp socket.

Encasing the stem 7 and lamp socket 10, 60 is an artificial candle 12 mounted in a candle holder 13, clamped onto the coupling 6 by a collar 14 which has screw-threaded engagement with the stem 7. A duplex lamp cord 15 is extended into the coupling 6 65 through an aperture 16, and is further extended into the stem 7 having an aperture 17 through which the lamp cord 15 is extended and then divided and attached to terminals 18 on the lamp socket 10 within the 70 artificial candle 12. On the outer end of the duplex lamp cord 15, is a plug 19 adapted to be screwed into an ordinary lamp socket for illuminating the candle.

Attached to each side of the hoop 5, is an 75 artificial wreath 20 designed to represent holly leaves and berries. As shown, these wreaths 20 are attached to the hoop 5 by a wire 21 spirally wound on the hoop 5, and over hidden portions of the wreaths, to bind 80 the same onto said hoop. The light bulb 11, which is designed to represent the flame of the candle, is positioned at the axis of the hoop 5, and in assembling the parts of the fixture, the light bulb 11 may be thus positioned by screwing the stem 7 into or out of coupling 6 or turning the cap 8 on said stem, or both, to longitudinally adjust the fixture. In some instances, it might be desirable to attach only a single wreath to the 90 hoop, for instance, when the same is to be hung on a wall or door. As a convenient means for hanging the wreath, I bend the hoop 5 directly over the candle to form an eye 22, which may be placed over a nail 95 or a suspending cord attached thereto.

Referring now to the invention as shown in Fig. 4, the artificial candle 23 has mounted in its upper end, a light bulb 24, and which candle is detachably supported from 100 hoop 5 by a coiled spring 25 secured in the lower end thereof with certain of its convolutions engaging the hoop 5.

What I claim is:

1. An illuminated Christmas wreath comprising 105 a transversely divided hoop, a wreath attached to the hoop, a coupling connecting the ends of the hoop, a stem extending radially into the hoop and attached to the coupling, a collar having screw-threaded engagement with a stem, a candle holder 110 encircling the stem and clamped between the

collar and coupling, a cap applied to the stem, a light socket secured to the cap, a light bulb in the light socket, an artificial candle in the candle holder and encasing the 5 stem, collar and light socket, and circuit wires extending into said candle through the coupling and stem and attached to terminals on the light socket.

2. An illuminated Christmas wreath comprising a transversely divided hoop, a wreath attached to the hoop, a coupling connecting the ends of the hoop, a tubular stem extending radially into the hoop and secured to the coupling by screw threads for endwise 10 adjustment, a cap adjustably applied to the 15 stem, a candle holder encircling the stem and clamped between the coupling and collar, a

light socket secured to the cap, a light bulb in the light socket, an artificial candle in the candle holder encasing the stem, collar and 20 light socket, and circuit wires extending into said candle through the coupling and stem and attached to terminals on the light socket.

3. An illuminated Christmas wreath comprising a hoop, a wreath attached to the 25 hoop, and an electric light bulb-equipped fixture attached to the hoop and arranged to hold said bulb within the hoop and wreath, said hoop being bent to form an eye at a point diametrically opposite said light 30 bulb.

In testimony whereof I affix my signature.

JACOB ANDRESEN.
